UNITED STATES PATENT OFFICE.

WILLIAM HETTERSCIED, OF GRAND RAPIDS, MICHIGAN.

TYPE-WRITER CABINET.

No. 909,798.

Specification of Letters Patent.

Patented Jan. 12, 1909.

Application filed February 3, 1908. Serial No. 414,184.

To all whom it may concern:

Be it known that I, WILLIAM HETTERSCIED, a citizen of the United States, residing at Grand Rapids, in the county of Kent and State of Michigan, have invented certain new and useful Improvements in Type-Writer Cabinets, of which the following is a specification.

My invention relates to improvements in type-writer cabinets for the support and storage of type-writers, and its objects are: First, to provide an all metal cabinet. Second, to provide a cabinet whose sides, cover, and front portions may be readily converted into side shelves or trays for receiving the paper to be written upon, and into a copy holder for retaining the copy in a convenient position when the cabinet is open, and third, to provide a type-writer cabinet that may be readily adjusted in height, and that is easily transportable from one position in an office to another. I attain these objects by the mechanism illustrated in the accompanying drawings in which:

Figure 1 is a front elevation of the cabinet complete, with its open position shown in outline. Fig. 2 is a side elevation of the cabinet portion opened to show the copy holder, and with its closed position shown in outline. Fig. 3 is a front elevation of the cabinet portion, partly in perspective, showing the side shelves or trays in position for receiving paper, &c. Fig. 4 is an edge view of the front of the cabinet showing the application of rollers to form a complete and convenient copy-holder, and Fig. 5 is a plan of the clamping bolts by means of which the top and the front of the cabinet are secured and supported.

Similar letters refer to similar parts throughout the several views.

The sides A A of the cabinet are pivotally connected with the bottom C, as at c c, both front and back, in such a manner that they may be swung down to the position indicated in Fig. 3, and by the dotted lines in Fig. 1 and will be there supported as shelves or trays, by the projecting ends a a bearing upon the lower surface of the bottom C' of the cabinet, and thus form deep trays for the reception of paper &c., that is to be used upon the type-writer, while the bottom C' of the cabinet is plain upon its upper surface for the reception of a type-writer or other desired article of its kind. When the cabinet is closed the sides A A assume the posi-

tion shown in Fig. 1, against the projecting sides E' of the back E and the cover D is closed down upon its upper edges with the front B in position between the front edges 60 of the sides, as indicated, so that the cabinet is closed so as to be made practically dust proof.

The top D of the cabinet is pivotally secured between the sides E' by means of the bolt F, in such a manner that it may be rigidly secured to the position shown by the solid lines in Fig. 2, or may be loosened up so that it may be closed, as shown in Fig. 1, and the front B of the cabinet is pivotally secured between the sides of the cover D by means of the bolt G' and nut G so that it may be securely clamped to place to form a copy holder, as in Figs. 2 and 3, or it may be closed to form the front of the cabinet, as in Fig. 1. The back E of the cabinet is stationary and has the right angled wings E' E' through which the bolt F passes and, by the pressure of the head f on one side, and the nut F on the other side, in combination with the long central cylinder F' between the sides of the cover, the cover and sides of the back may be rigidly secured to place without danger of deforming the sides E', and a like condition exists with the bolt 80 G', having the head g and the nut G, that presses through the sides of the cover and the cylindrical end B' of the front B so as to press the sides of the cover D firmly between the cylindrical end of the front and 85 the head g, on one side, and the nut G on the other side of the cabinet, forming a friction joint for holding the cover.

With my better cabinets I place a permanent roller N upon the front B and secure an adjustable roller N' to the front by means of springs O for the purpose of forming a cheap, convenient and thoroughly operative copy holder with which the copy P may be readily manipulated, as desired, when copying it with the type-writer.

I find it very advantageous to form outwardly projecting wings d d upon the edges of the sides of the cover D to project out over the edge of the top of the sides A A 105 when the cabinet is closed, as it makes a better appearance than a thin edge would, and assists greatly in forming dust proof joints at these lines of connection.

For the purpose of making the cabinet as 110 useful and convenient as possible, I have extended the cross bar H' down far enough

to permit me to place a drawer H below the cabinet and, if desired, a slide h' may be placed between the drawer and the bottom of the cabinet.

5 My appliance for rendering the cabinet vertically adjustable consists of the standard J having diverging legs K secured to the standard by the clamping ring L. The upper end of the standard J is slotted at the 10 top, as at j, so that it may be clamped firmly to the screw standard I by means of the clamping ring M to prevent the cabinet from turning around when in use, and the upper end of the screw I is secured in the bearing h 15 so that the bearing cannot be made to revolve except as the screw revolves with it. The screw thread on the screw I should be formed at as great an incline as possible so that it will require but a few revolutions of 20 the screw to raise or lower the cabinet to the position desired.

n, in Fig. 3, represents a small wheel, knob or hand piece with which to manipulate the rollers N and N' to adjust the copy 25 as desired.

Having thus fully described my invention, what I claim as new, and desire to secure by Letters Patent of the United States, is:

1. In a type-writer cabinet, a permanent 30 bottom, a back extending up at right angles from the bottom and having its side edges projected forward at right angles with the back, a cover having a cylinder formed across

its back end, a bolt passing through said cylinder and engaging the forwardly projecting edges of the back, a front pivotally secured to the cover with a securing bolt and nut, and arranged to form a copy holder, and sides pivotally secured to the bottom to fold down and form trays. 35

2. In a type-writer cabinet, a bottom having sides pivoted thereto and a back projecting upward from its rear edge, forwardly projecting sides connected with the back, a cover pivotally secured between the 40 projecting sides, a front pivotally secured to the cover, a bolt for clamping the front firmly in place to form a closed front or an adjustable copyholder for the cabinet. 45

3. In a type-writer cabinet, a bottom having an upwardly projecting back with forwardly projecting sides thereto, a cover clamped at one end between the projecting sides, a front clamped at one edge to the front end of the cover, to form a front when 50 the cabinet is closed, and an adjustable copy holder when the cabinet is open, and sides pivotally secured to the bottom in position to fold down and form side trays at each side of the bottom. 55

Signed at Grand Rapids Michigan January 25 1908.

WILLIAM HETTERSCHIED.
